UNITED STATES PATENT OFFICE.

JAMES M. BOLTON, OF ATLANTIC, IOWA.

ADDRESSING-MACHINE.

SPECIFICATION forming part of Letters Patent No. 236,143, dated January 4, 1881.

Application filed August 16, 1880. (No model.)

To all whom it may concern:

Be it known that I, JAMES M. BOLTON, of Atlantic, in the county of Cass and State of Iowa, have invented an Improved Addressing-Machine, of which the following is a specification.

The object of my invention is to save time, labor, and expense in printing the addresses of newspaper-subscribers upon papers or wrap-
pers repeatedly, as required to mail a copy of each issue of the publication to each sub-
scriber.

Heretofore addresses have been set up in type and printed upon slips, from which slips they were cut off consecutively and pasted upon the papers or wrappers. Addresses set up in type or cut into blocks have been carried by galleys or endless chains to consecutively come into contact with inking-rollers
and under the platen of an addressing-machine that could be operated by means of a hand-lever or treadle to make impressions upon papers placed under the platen. These modes require the use of movable type, and when large lists of addresses are to be printed the expense of procuring and retaining the addresses in forms and galleys is burdensome. Endless belts have also been formed of stencil-plates specially constructed for the purpose, and used in an addressing-machine to accomplish the results contemplated. A paper ribbon has also been perforated and used as a stencil in printing addresses.

To dispense with movable type I construct an addressing-machine adapted to print addresses consecutively and repeatedly and rapidly from common and cheap stencil-plates, as hereinafter fully set forth.

Figure 1 of my drawings is a longitudinal section of my machine. Fig. 2 is a perspective view of the complete machine. Together they clearly illustrate the construction and operation of my complete invention.

a is the bed-plate and base of my stencil-plate printing-press. It may be made of wood, iron, or any other suitable material, and vary in size as desired.

b b are side pieces rigidly secured to the side edges of the bed-plate *a* by means of screws, or in any suitable way, to form a frame for my complete press. They are uniform in size and

shape, about twice as long as the bed-plate, and twice as wide as the depth or thickness of the bed-plate.

c c are driver-rollers mounted in the frame 55 near the ends of the bed-plate *a*, and in a horizontal line with the vertical center of the bed-plate.

d d is an endless pad stretched over the rollers *c* in such a manner as to inclose the 60 bed-plate *a* and to stretch over the top surface of the bed-plate, to perform the functions of an inking cylinder or pad, and also of a carrier.

f is a ratchet-wheel fixed to one of the ends 65 of the axle or one of the gudgeons of one of the rollers *c*, that project outward through the bearings formed in or attached to the side pieces, *b*, of the frame.

g is a bifurcated hand-lever pivoted to the 70 combined roller and ratchet *c f*.

h is a gravitating pawl pivoted to the lever *g* in such a position that it will engage the ratchet-wheel *f*.

i is a bar extending downward from the 75 central portion of the pivoted hand-lever *g*. It terminates in a platen-head adapted in size and form to cover an address cut into a stencil-plate, and to press a paper or wrapper downward through an auxiliary bed-plate, *k*, 80 that has an opening corresponding with the platen-head, and is fixed to the frame *b* to extend over the elastic endless and movable inking-pad *d*, and also over the fixed bed-plate *a*.

m represents a grooved slide, galley, or belt, 85 into which the ends of stencil-plates of individual addresses are inserted, to be held together and to form a continuous belt that can be placed upon the endless pad and carrier *d* and moved under the platen-head *i* by the intermittent motions of the lever-handle *g*, as required to print addresses successively by means of the connected stencil-plates. The slide *m*, thus connected with the continuous belt of stencil-plates and resting upon the endless 95 carrier *d*, will be moved, jointly with the plates, by the operation of said endless carrier, upon which the slide and plates jointly rest, and after they jointly pass from under the auxiliary bed-plate *k* they can be readily lifted from the 100 machine and stored away.

n is the frame of an inking apparatus, in

which a series of rollers, 1 2 3, is mounted in such a manner that it can be readily placed in the rear end of the frame *b b* and in contact with the endless inking-pad *d*.

5 *s* is a roller mounted in the front end of the frame *b b* to hold the stencil-plates and retain them on a level with the endless carrier and pad *d*, upon which they are to be moved rearward under the auxiliary bed-plate *k* and 10 platen-head *i*.

In the practical operation of my machine thus formed I place it upon a table or platform, and the papers that are to be marked contiguous thereto. The addresses, previously cut 15 into the stencil-plate and alphabetically or numerically arranged in slides, galleys, or belts, are then placed under the auxiliary bed-plate and passed through the machine by the operation of the lever-handle *g*. When the first 20

stencil address can be seen through the opening of the plate *k* one of the newspapers or 25 wrappers is placed upon the auxiliary bed *k* and the platen-head *i* brought down upon it with pressure sufficient to meet the resisting

force of the fixed bed *a* and to cause the elastic inking-pad *d* to be pressed upward, thereby, through the stencil, to make an impression upon the paper or wrapper. The upward motion 30 of the handle *g* required to free the paper will

cause the pawl *h* to actuate the combined ratchet-wheel and roller *f e*, and thereby move 35 the carrier and inking-pad and carry the movable slide *m* and the stencil-plates held in and carried by said slide rearward. Each upward motion of the lever-handle will thus advance

the stencil addresses, and each downward motion will print an address upon the paper or wrapper placed under the platen-head, and a complete list of subscribers' addresses repeatedly printed, as required, for each edition or 40 issue of the publication.

I claim—

1. The combination of the frame *a b b*, the rollers *c c*, the endless and elastic carrier and inking-pad *d*, the slide *m*, holding and carrying stencil-plates, the ratchet-wheel *f*, and the hand-lever *g*, carrying the pawl *h*, substantially as shown and described, for the purposes specified. 45

2. The combination of the endless carrier and pad *d*, the auxiliary bed-plate *k*, the movable slide or galley *m*, carrying stencil-plates, and the hand-lever *g*, carrying a platen-head, *i*, substantially as shown and described, to operate in the manner set forth. 50

3. The improved addressing-machine composed of the following elements and sub-combinations, to wit: the bed-plate and frame *a b b*, the endless carrier and inking-pad *d*, rollers *c c*, the operative mechanism *f g h*, the platen-head *i*, the auxiliary bed-plate *k*, the inking apparatus *n 1 2 3*, and a slide or device adapted to hold together and carry stencil-plates, substantially as shown and described, to be operated in the manner set forth. 60

JAMES M. BOLTON.
